UNITED STATES PATENT OFFICE

THEODORE SCHERF, OF ENGLEWOOD, NEW JERSEY.

PAPER.

No. 860,697.

Specification of Letters Patent.

Patented July 23, 1907.

Application filed November 19, 1906. Serial No. 343,961.

To all whom it may concern:

Be it known that I, THEODORE SCHERF, a citizen of the United States, residing at Englewood, in the county of Bergen and State of New Jersey, have invented certain new and useful Improvements in Paper, of which the following is a specification, reference being had to the drawings accompanying and forming part of the same.

In numerous uses to which paper is put it is desirable that the paper be as pliable or soft as possible, consistent with the strength necessary for the given purpose. For example, a paper bag should be made of paper possessing a considerable degree of softness or pliability. Made of such paper the bag conforms more closely to its contents, thereby distributing the weight or pressure of the contents more evenly, and its mouth is more easily gathered or folded by the hand and can be more securely closed, as is particularly desirable where the contents of the bag are of a powdered or granular character. Paper to be wrapped around electrical conductors or other parts of electrical apparatus for the purpose of insulating the same should also be soft and pliable. Such paper conforms more closely to the contour of the object to be covered, and the work of wrapping or covering can be done more easily and rapidly. Paper for the manufacture of artificial or imitation leather should also be of the same soft and pliable character to produce the most effective imitation of the natural article, both for the desired flexibility and to permit the production of embossed patterns without cracking or tearing under the pressure of the embossing dies. Numerous other uses might be mentioned where paper of the character described is desirable, but those mentioned are sufficient to show its wide and diversified field of utility.

Practically all the papers now made, however, which possess the tensile strength necessary for their manifold uses, possess also an undesirable degree of stiffness, which does not permit them to bend easily and frequently causes them to form hard creases or folds when bent on an arc of short radius, or to become creased or wrinkled in handling. This lack of pliability is a serious drawback for many purposes for which the paper is used, as already pointed out, and efforts have therefore been made, with more or less success, to provide paper which shall possess the desired degree of softness or pliability and also the necessary strength.

My present invention has for its chief object to provide paper having these much desired characteristics and a further object of the invention is to provide paper which shall also have surface ribs or ridges on one or both of its surfaces.

For producing paper of such character I prefer to use multilayer paper, that is, paper composed of two or more films or layers. This paper is passed through suitable mechanism which has the effect of softening the

sizing and the fibers of the paper and at the same time loosening or separating portions of the component films or layers from each other. Paper so treated will, on being bent more or less sharply, show bulges or blisters on the inner surface of the bend. The paper having its layers thus loosened may be drawn in contact with one or more smooth bars or blades, which have the effect of folding these bulges or blisters down upon the body of the paper, thus producing ribs or ridges. The result is a paper of great softness and pliability, one or both surfaces of which, according as one or both surfaces have been passed in contact with the ribbing device or devices, are covered with ribs or ridges where the layers of the sheet have been loosened or separated.

A simple and convenient apparatus for producing paper of this character is illustrated, somewhat diagrammatically, in the annexed drawing. Therein

Figure 1 shows the apparatus in vertical longitudinal section, and shows also a web or sheet of paper in course of treatment. Fig. 2 is a sectional perspective view, on an exaggerated scale, of a sheet of multilayer paper bent on an arc of short radius, showing the separation of the layers and the bulging or blistering produced by the bending. Fig. 3 is a detail sectional view, on an exaggerated scale, showing the operation of a ribbing bar in producing a rib or fold. Fig. 4 is a sectional view, on a much exaggerated scale, showing the nature of the ribs or folds. Figs. 5 and 6 are plan views showing the appearance of paper having surface ribs or ridges, the ribs in the first figure running substantially in the same direction and those in the second figure crossing each other.

Referring now more particularly to Fig. 1, A, A' are rotating, bladed kneading rolls, the blades of which intermesh and are preferably longitudinal of the axes of the rolls. B indicates a web or sheet of paper engaged by the rolls, and it will be seen that the effect of the blades is to bend the paper more or less sharply over their edges, first in one direction and then in the other.

The natural result of such action would be to leave the paper in a corrugated or crimped condition, but such a result is prevented by causing the paper to pass through the rolls at a higher rate of speed than that at which it would travel if carried forward only by the rolls themselves.

Any convenient means may be provided for causing the paper to travel faster than the feed of the rolls, such as, for example, the mechanism shown in my co-pending application, Serial No. 322,481, in which an apparatus of the general character herein briefly outlined is described and claimed broadly.

The result of causing the paper to travel faster than the peripheral speed of the rolls is that the paper is not only bent over the blades in succession, but is also drawn firmly over their edges. This grip of the paper relative to the blades causes the line of fold over the edge of the blade to move slowly backward until the

blade is by the rotation of the roll carried out of contact with the paper. In the meantime the paper is engaged by succeeding blades of the rolls and the action just described is repeated on each blade, so that every portion of the paper is subjected to one or more kneading or breaking and drawing actions and is thereby reduced to a soft and pliable condition.

As previously stated, some papers, particularly the heavier kinds, are formed of two or more layers or films 10 united, usually in the wet state. Thus united the several layers form a single, firm sheet of paper. The action of the kneading rolls on such paper is not only to render the paper soft and pliable in the manner described, but also to loosen the layers from each other 15 at numerous points, leaving them adhering at intermediate points. This result can readily be observed by bending the paper, causing the separated portions of the layers on the inside of the bend to bulge out and form blister-like protuberances, as shown at C, Fig. 2. 20 This loosening of the layers composing the sheet can be utilized to good advantage for making ribs or ridges on one or both surfaces of the paper. To produce the desired ribs the paper is drawn in contact with one or more bars or similar devices, as shown in Fig. 1, in 25 which four bars, indicated by D, E, F, G, are shown, with the paper in contact therewith. The effect of the bars, the action of a single bar being shown at H, in Fig. 3, is to form the blisters or bulges previously described and to fold the same firmly on the body of 30 the paper, producing ribs or folds like those shown at I in Fig. 4. The ribs or folds are generally of various lengths, according to the size of the blisters from which they are produced. If the bars producing the folds are substantially parallel with each other the folds will 35 run more or less in the same general direction, determined by the angle which the bars make with the path of the paper. Thus, if the bars are at right angles to the paper as it is drawn over them, the ribs will run approximately at right angles to the length of the paper, 40 as shown in Fig. 5. If one bar is arranged at an angle to the direction of movement of the paper, and another bar at an angle to the first, the two will produce two sets of ribs, crossing each other, as will be readily understood, thus giving an effect like that shown in Fig. 6. 45 In general, paper treated as above described will be found to be singularly soft and pliable, with the stiffness and slight springiness or resiliency, due to the sizing, entirely eradicated; although the strength of the paper, which is due in large measure to the sizing, 50 is not materially impaired, if at all. All kinds of paper,

issuing from the kneading rolls, will be found to have perfectly smooth surfaces, even the multilayer paper referred to above, the ribbed effect being produced in the latter by the ribbing bars above described or equivalent devices. The unribbed paper is wholly devoid 55 of air pockets, cells, or blisters, the component layers being merely loosened from each other. The ribbed paper is also devoid of air cells, etc., since the cells or blisters formed by bending the paper do not exist after the ribs or folds are formed. The surface-ribs may 60 therefore be described as solid, by which is meant that the rib is in no sense the outer wall of a cell, pocket, or blister. The ribbed paper is not corrugated in the proper sense of the term, as would be the case if the paper were not drawn positively over the blades of the 65 kneading rolls. Before the rib-folds are produced the paper can scarcely be distinguished in appearance from the same grade and kind of paper unsoftened.

While in respect to its limpness and pliability the 70 paper resembles unsized paper, the chief characteristic imparted by the sizing, namely, strength, is not impaired to any appreciable degree; while the non-absorptive properties of the paper, also due to the sizing, are not materially impaired, that is, the paper 75 does not act like blotting paper.

As previously pointed out, my softened paper has marked utility for many purposes, among which may be mentioned the manufacture of paper bags and similar receptacles; imitation leather for book-bindings, box-coverings, and other uses to which such product 80 is commonly employed; for insulation purposes, as a wrapping for conductors and other parts of electrical apparatus. For the latter purpose the ribbed paper is particularly advantageous, as the ribs prevent the paper being wrapped solid and produce numerous 85 interstices or air-spaces in the wrapping, thereby increasing its insulating properties.

What I claim is:

1. As a new article of manufacture, sized multilayer paper rendered soft and pliable, the stiffness due to the 90 sizing being substantially eradicated, having portions of its component layers loosened from one another, and devoid of air cells or pockets as set forth.

2. As a new article of manufacture, sized multilayer paper rendered soft and pliable, the stiffness due to sizing 95 being substantially eradicated, and having portions of its component layers loosened from one another and folded into solid ribs or ridges, as set forth.

THEODORE SCHERF.
